Primary Examiner — Patricia Palasik(74) *Attorney, Agent, or Firm* — Honigman Miller Schwartz and Cohn LLP(57) **CLAIM**

The ornamental design for a mobile human interface robot, as shown and described.

DESCRIPTION

FIG. 1 is a front perspective view of a mobile human interface robot, showing our new design;

FIG. 2 is a rear perspective view thereof;

FIG. 3 is a side perspective view thereof;

FIG. 4 is a front view thereof; and,

FIG. 5 is an enlarged top plan view thereof.

The dashed lines in the drawing views depict portions of the design that form no part of the claim.
